LATCH MECHANISM

Walter P. Cousino, Detroit, Mich., assignor to
 Chrysler Corporation, Highland Park, Mich., a
 corporation of Delaware

Application July 21, 1941, Serial No. 403,319

10 Claims. (Cl. 70—146)

The invention relates to a latching mechanism and more particularly to a locking device for such a mechanism which may be locked or unlocked from either side of a door.

Automobile bodies have been provided with combined latches and locks which can be locked on the inside but cannot be unlocked from the outside, or locked from the outside but cannot be unlocked from the inside.

It is an important object of this invention to provide a mechanism which will permit the vehicle door to be locked from the inside and unlocked from the outside and to be locked from the outside and unlocked from the inside.

Another object of the invention is to provide a mechanism which cooperates between a latch control member and a key locking member such that the door can be locked by operating the latch control member to control the key lock. By this arrangement the door can never be in its locked position when closing without the use of the key locking member. By this arrangement of parts it is impossible to close the doors of a vehicle with the key inside and lock the operator outside of the vehicle, yet when the operator is inside the vehicle all doors can be locked so that they cannot be unlocked from the outside without the use of the key.

A further object of the invention is to provide a latch control member which operates in two directions from a normal position to control the locking device when moved in one direction and to control the latching mechanism when moved in the opposite direction and to provide means for returning the latch control member to its normal position.

Another object of the invention is to provide a simple and inexpensive member which may be readily applied to a standard door latching and locking mechanism.

Still another object is to provide a lock for an automobile that, having previously been locked by an inside control, may be unlocked by a key from the outside, and that, having previously been locked from the outside by a key, may be unlocked by an inside control. In automobiles of the present day it is frequently the practice to provide key-operated door locks at opposite sides of the automobile so that the operator may leave through one of two doors and lock by key the door through which he has left, having previously locked by an inside control the opposite door. It is often inconvenient for him to re-enter the automobile through the door through which he left, and yet if the lock effected by the

inside control prevents use of the key for unlocking the door from the outside, he is forced to use the door through which he left. It is, therefore, very desirable that a door be capable of unlocking from the outside by key after being locked by inside control. The reverse is also desirable, for otherwise it will be impossible for an operator to leave a car by a certain door if he has entered by another door, and the said certain door had been previously locked from outside by a key.

Other objects and advantages of the invention will more fully appear from the following description taken in connection with the accompanying drawings, in which:

15 Fig. 1 is a sectional view through a portion of an automobile body showing the controls for the latching mechanism in a door;

Fig. 2 is a side view of the latching mechanism, parts being broken away and in section;

20 Fig. 3 is an end view of the latching mechanism, parts being broken away and in section;

Fig. 4 is a perspective view showing the salient features of the invention;

Fig. 5 is a sectional view taken on line 5—5 of Fig. 2; and

Fig. 6 is an elevational view of the remote control handle as viewed on line 6—6 of Fig. 1.

Referring to the drawings I have shown a portion of the side wall of an automobile body 10 and a door 12 hinged at 14 to one side of the body 10. The usual dovetails 16 are provided to properly align the door with body when in closed position. The latching mechanism is illustrated at 18. An outside handle 20 is operatively connected to the latching mechanism 18 through a shank 22 and a key tumbler lock 24 is operatively connected to the locking mechanism of the latching mechanism 18 through a shank 26. An inside handle 28 is connected to the latching mechanism through a link 30.

The several parts of the latch and lock mechanisms are supported on an angle plate 32 having a side wall 34 and an end wall 36. The side wall 34 is provided with an inwardly spaced plate 38, secured to the side wall by bent ears 40 projecting through openings in the side wall. The end wall 36 is provided with an inwardly spaced plate 42 and an outwardly spaced plate 44. The plate 42 is secured to the end wall 36 by bent ears 46 and the plate 44 is secured to the end wall 36 by rivets 48.

A latch member in the form of a star wheel 50 is rotatably supported in an opening 52 in the end wall 36 and is mounted on a shaft 54 supported by the plates 42 and 44. The pro-

jections 58 on the star wheel 50 engage a keeper in the form of a projecting lug 58 in the door casing and when the wheel 50 is prevented from turning the door is held in latched position. A pawl 60 is pivotally mounted on a pin 62 and swings into and out of the path of the projections 56'. The projections 56 and 56' are in alignment and are separated by an annular rib 64. A coil spring 66 normally holds the pawl in the position shown in Fig. 3 so that the star wheel 50 is prevented from rotating to thereby hold the door in latched position.

A roll back 68 is carried by the handle shank 22 and engages a bent over edge portion 70 on a sliding plate 72. The plate 72 is provided with a lug 74 which is positioned to engage a flange 76 on the pawl 60. By turning the handle 20, the roll back 68 moves the plate 72 downwardly so that the lug 74 engages the flange 76 to swing the pawl 60 out of the path of the projections 56' thereby permitting free rotation of the star wheel 50. A spring 71 urges the plate 72 upwardly.

The parts as shown in Figs. 2, 3, and 4 are in locked position. The key tumbler shank 26 is provided with a cam 78 which, as shown in Fig. 4, is in the path of the plate 72 preventing downward movement of the plate 72. By rotating the key cylinder 24 in a direction indicated by the arrow, by the vertically disposed key 25, the segment 78 is rotated out of the path of the plate 72 and the outside door handle may be turned to free the star wheel 50.

The link 30 is connected to a pivotally mounted plate 80. The latter is provided with a lug 82 which engages the flange 76 for swinging the pawl 60 by moving the inside handle 28. Either handle may be moved to operate the pawl 60 independently of the other and the inside handle 28 may be moved to operate the pawl 60 even though the parts are in the key locked position as shown.

The link 30 is connected to the inside handle 28 through a link 84 having a flat face 86 engaged by a spring 88 to hold the link 84 in a normal central position. The inside handle 28 may be moved in either direction and when released will return to its normal central position. When the handle is moved in one direction the star wheel 50 is released for unlatching the door and when moved in an opposite direction the mechanism may be locked as will be more fully explained.

In order to provide a means for operating the key cylinder 24 through movement of the inside handle 28, I have provided a link 90 with projecting ears 92, 94 and 96. This link may be a stamping from sheet metal with the ears bent from the edges of the metal. The ear 92 engages a slot 98 in the cam 78 so that vertical movement of the link 90 causes rotation of the cam 78 throwing it into or out of the path of the plate 72. The ear 94 is positioned underneath the flange 76 to be moved thereby. The ear 96 is positioned above a projection 100 on the plate 80.

It will be observed, particularly from Fig. 2, that the slot 98 lies at an about 45° to the horizontal when the cam 78 is in the locking or blocking position, and that the slot is at all times engaged by the ear 92 of the link 90. A clockwise rotation of the plate 80 by the handle 28 causes the lug 82 to move downwardly the flange 76 and therewith to disengage the pawl 60 from the wheel 50 for opening the door. If the cam

78 happens to be in the blocking position of Fig. 4, the flange 76 contacts the flange 94 in its downward movement, moving the link 90 downwardly and rotating the cam 78 clockwise out of a position blocking the plate 72. Thereafter the door may be opened by the outside handle. When the handle 28 is released, it returns to its neutral position, in which the lug 82 is lifted out of contact with flange 76 so that the pawl 60 is returned to engagement with the wheel 50, and thereby the door is again latched. Return of the handle 28 and the plate 80 to the neutral position of Fig. 4 will not cause a relocking of the door, for the projection 100 on the plate 80 will move only up to the flange 96 on the link 90. This is evident because the space between the lug 100 and the flange 96 shows that if the cam 78 were in unblocking position, the flange 96 would be lowered no more than to contact the lug 100. Conversely the return of the inside handle 28 and the plate 80 to neutral position will do no more than make contact between the lug 100 and the flange 96, and so the cam 78 will be left in unblocking position. If the cam 78 is in unblocking position, and consequently the door is unlocked, a counterclockwise rotation of the plate 80 produced by a movement of the link 30 due to rotation of the handle 28 will cause an upward movement of the lug 100 to act by contact with the flange 96 to move the link 72 upwardly and to rotate the cam counterclockwise to the blocking position of Fig. 4. Release of the handle 28 causes a return of the plate 80 to the neutral position of Fig. 4, in which the lug 100 and the flange 96 are spaced from one another. This spacing permits the cam 78 to be rotated to unblocking position by means of a key inserted from the outside of the door in the lock 24 without interference from the plate 80 and the inside handle 28. In order to cooperate with this mechanism as shown and described, the lock 24 is of a type having a lost motion built into it. Since such locks, and the details thereof, are known to the art and are available, and since the details form no part of this invention, the internal construction has not been further shown or described, and reference is made to Figs. 12-17 of Dall Patent No. 2,246,781 for a showing of a lock of this type.

In the manipulation of the device, assuming that the key cylinder 24 is in its locked position, the outside handle 20 cannot be moved because the cam 78 is in the path of the plate 72. The operator then unlocks the mechanism by turning the cam 78 in a direction indicated by the arrow out of the path of the plate 72. The outside handle 20 can then be moved, sliding the plate 72 downwardly and swinging the pawl 60 out of the path of the star wheel 50 permitting it to rotate freely on the shaft 54. When the handle is released the plate 72 is returned to its normal position by the spring 71. When the door is closed the star wheel 50 can rotate in a clockwise direction when one of the projections 56 strikes the lug 58 but it is held against counterclockwise rotation by the pawl 60.

When the operator is inside the car and wishes to lock the door so that it cannot be opened from the outside he moves the inside door handle 28 in a direction to move the projection 100 upwardly against the ear 96. This moves the link 90 upwardly which by engagement with the ear 92 in the slot 98 causes rotation of the cam 78 in a counterclockwise direction into the path of the plate 72. Should the operator wish to leave

the car through another door with the first door locked, he can unlock the first from the outside by the use of the key lock 24 because the projection 100 has moved downwardly away from the ear 86 by means of the spring 88 and the link 90 is free to be moved downwardly when the key lock is turned to move the cam 78 out of the path of the plate 72.

By this arrangement of parts it is impossible for an operator to lock himself out of the car by leaving his key inside the car as has happened heretofore many times. When the operator uses the inside handle 28 to open the door when it has been locked from the outside with the key lock the link 90 moves the cam 78 out of the locked position. The act of closing the door will unlock the device so that it will be necessary to lock the door with the key from the outside if the operator is outside of the car. The rotation of star wheel 50 swings the pawl 60 and the flange 76 forces the link 90 downwardly rotating the cam 78 out of the path of the plate 72. If the operator is inside the mechanism can be locked by the inside handle 28 as described above.

It will be understood that various changes including the size, shape and arrangement of parts may be made without departing from the spirit of my invention and it is not my intention to limit its scope other than by the terms of the appended claims.

I claim:

1. In a latch mechanism, a latch member arranged to operatively engage an associated keeper to hold associated closure members in predetermined position, means externally of the closure members and operatively associated with said latch member to render said latch member ineffective to so hold said members, a locking member movable to block the movement of said latch operating means, means internally of the closure members operatively associated with said latch member to render said latch member ineffective and operable independently of said external means, and a link operable between said internal control means and said locking member to effect movement thereof from a locked position to an unlocked position or from an unlocked position to a locked position.

2. In a latch mechanism, a rotatable member having projections for engagement with an associated keeper, a pawl for engagement with one of said projections to prevent rotation of said rotatable member in one direction, a slideable member operatively associated with said pawl to swing the latter into and out of holding position with said rotatable member, control means for moving said slideable member, a locking member movable to block the movement of said slideable member, a second control means operatively associated with said pawl to swing the latter into and out of holding position with said rotatable member independently of said first named control means, and a link operable in one direction to move said locking member into the path of said slideable member and in an opposite direction to move said locking member out of the path of said slideable member, said link being associated with said second control means whereby movement of the latter causes movement of said link in opposite directions.

3. In a latch mechanism for a door, a latch device for holding the door in closed position, a control for releasing said latch device, a lock comprising a rotatable cam movable into and out of the path of said control, a second control for

said latch device, and a member operable between said cam and said second control for moving said cam into and out of the path of said first named control.

4. In a latch mechanism for a door, a latch device for holding the door in closed position, an outside control for releasing said latch device including a movable plate, an inside control for releasing said latch device, a rotatable key operated cam movable into and out of the path of said movable plate, a member forming a connection between said inside control and said cam, said member at one end thereof having a projection received in a recess in said cam and a projection at the other end thereof for engagement with said inside control.

5. In a latching mechanism of the type having a pawl-retained rotatable latch member, an outside rollback for releasing the pawl, and a separate inside lever system for releasing the pawl, a locking member adapted to be positioned in alternate positions respectively permitting and preventing operative movement of the roll-back, and a link connected to the locking member and independently engageable by said lever system when in one position and by said pawl to enforce the positioning of the locking member in its non-locking position, said link also being engageable by said lever system upon an alternate predetermined movement thereof to enforce the positioning of the locking member in its locking position.

6. In a latch mechanism, a pawl, a door latch member adapted to be engaged by the pawl, an outside rotatable handle, a plate member actuated by rotation of the handle to disengage the pawl from the latch member, a locking member movable into and out of position to block the movement of the plate member, means operable from the outside for moving the locking member, an inside handle, a lever system extending from the inside handle to the pawl and operable upon predetermined movement of the inside handle to disengage the pawl from the latch member, and a link connected to said locking member and engageable by said lever system upon said predetermined movement to move said locking member from blocking to unblocking position, said lever system, upon another predetermined movement of the inside handle engaging said link to move the locking member to blocking position, whereby the latch may be operated and locked from either the inside or outside independently of a previous actuation of the locking member from the opposite side.

7. In the latching mechanism set forth in claim 6, spring means for restoring the inside handle to a neutral position after manual release from either of its predetermined manipulating positions.

8. In combination, means for holding a door closed, a first control operable from one side of the door for releasing the holding means, blocking means movable to and from a position blocking the first control from releasing the holding means, a second control operable from the said one side of the door for moving the blocking means to and from blocking position, a third control operable from the other side of the door so as to be shiftable from a neutral position in one direction to a first extreme position to move to blocking position the same blocking means controlled by the second control and shiftable in another direction from the neutral position to a second extreme position to move the

said same blocking means out of blocking position and to release the holding means, and means for urging the third control to neutral position from the first extreme position for causing the said same blocking means to be free to be moved out of blocking position by the second control after having been moved there by the third control.

9. In combination, means for holding a door closed, a first reciprocable member shiftable in a certain direction for releasing the holding means, a first control operable from the outer side of the door for shifting the first reciprocable member in the said certain direction to release the holding means, a blocking member angularly movable to and from a blocking position engaging the first reciprocable member for preventing movement of the same in the said certain direction and therewith release of the holding means, a key control operable from the outer side of the door for angularly moving the blocking member to and from blocking position, a second reciprocable member positioned alongside the first reciprocable member and shiftable in the said certain direction to move the blocking member out of blocking position and shiftable in the opposite direction to move the blocking member into blocking position, and a third control operable from the inside of the door so as to be movable in one direction from a neutral position to shift the second reciprocable member in the said opposite direction for moving the blocking member to blocking position and to be movable in another direction from the neutral position to shift the said second reciprocable member in the said certain direction for moving the blocking member out of blocking position and for releasing the holding means.

10. In combination, means for holding a door closed, a first reciprocable member shiftable in a certain direction for releasing the holding means, a first control operable from the outer side of the door for shifting the first reciprocable member in the said certain direction to release the holding means, a blocking member angularly movable to and from a blocking position engaging the first reciprocable member for preventing movement of the same in the said certain direction and therewith release of the holding means, a key control operable from the outer side of the door for angularly moving the blocking member to and from blocking position, a second reciprocable member positioned alongside the first reciprocable member and shiftable in the said certain direction to move the blocking member out of blocking position and shiftable in the opposite direction to move the blocking member into blocking position, and a third control operable from the inside of the door so as to be movable in one direction from a neutral position to shift the second reciprocable member in the said opposite direction for moving the blocking member to blocking position and to be movable in another direction from the neutral position to shift the said second reciprocable member in the said certain direction for moving the blocking member out of blocking position and for releasing the holding means, and means for urging the third control member in the said other direction after movement thereof in the said one direction bringing the blocking member to blocking position for causing the said blocking member to be free to be moved out of blocking position by the outside key control after having been moved there by the third inside control.

WALTER P. COUSINO.
